US00D988647S

(12) United States Design Patent (10) Patent No.: US D988,647 S
Martin et al. (45) Date of Patent: * Jun. 13, 2023

(54) BOOT

(71) Applicant: ROTHY'S, INC., San Francisco, CA (US)

(72) Inventors: William Roth Martin, San Francisco, CA (US); La Vion Gibson, San Francisco, CA (US); Erin D. Lowenberg, San Francisco, CA (US); Yen-Hung Lin, San Francisco, CA (US)

(73) Assignee: ROTHY'S, INC., San Francisco, CA (US)

() Term: 15 Years

(21) Appl. No.: 29/750,808

(22) Filed: Sep. 16, 2020

(51) LOC (14) Cl. 02-04

(52) U.S. Cl.

USPC D2/910; D2/909

(57) CLAIM

The ornamental design for a boot, as shown and described.

DESCRIPTION

FIG. 1 is a front left perspective view of a first embodiment of a boot showing our new design;

FIG. 2 is a back right perspective view of the design shown in FIG. 1;

FIG. 3 is front view of the design shown in FIG. 1;

FIG. 4 is a back view of the design shown in FIG. 1;

FIG. 5 is a right side view of the design shown in FIG. 1;

FIG. 6 is a left side view of the design shown in FIG. 1;

FIG. 7 is a top view of the design shown in FIG. 1;

FIG. 8 is a bottom view of the design shown in FIG. 1;

FIG. 9 is a front left perspective view of a second embodiment of a boot showing our new design;

FIG. 10 is a back right perspective view of the design shown in FIG. 9;

FIG. 11 is front view of the design shown in FIG. 9;

FIG. 12 is a back view of the design shown in FIG. 9;

FIG. 13 is a right side view of the design shown in FIG. 9;

FIG. 14 is a left side view of the design shown in FIG. 9;

FIG. 15 is a top view of the design shown in FIG. 9; and,

FIG. 16 is a bottom view of the design shown in FIG. 9.

FIGS. 7 and 15 include dash-dot-dash lines. The dash-dot-dash lines show portions of the boot that form no part of the claimed design.

1 Claim, 16 Drawing Sheets
